Alfred E. Schumel, Attorney

UNITED STATES PATENT OFFICE.

JAMES L. HICKEY, OF CRANE, AND JOHN KRACHT, OF MILWAUKEE, WISCONSIN.

RATCHET WRENCH.

Application filed April 24, 1920. Serial No. 376,255.

To all whom it may concern:

Be it known that JAMES L. HICKEY and JOHN KRACHT, residing, respectively, at Crane, in the county of Rusk, State of Wisconsin, and at Milwaukee, in the county of Milwaukee and State of Wisconsin, have invented new and useful Improvements in Ratchet Wrenches, of which the following is a specification.

10 The object of the invention is to provide a simple and efficient ratchet wrench for general machine and repair work, capable of being adjusted to operate at various angles to facilitate reaching bolts and nuts in more 15 or less inaccessible positions and having the adjusting means disposed within the contour of the wrench and shank so as to economize space and minimize the space within which the tool may be effectively employed, 20 and with these objects in view the invention consists in a construction and combination of parts of which a preferred embodiment is shown in the drawing, wherein:

Figure 1 is a side view of the wrench.

25 Figure 2 is an edge view.

Figure 3 is a side view partly broken away to show the operating means.

The tool consists essentially of a shank 10 having a handle or grip portion 11 and bifurcated as indicated at 12 for the reception 30 of a pivotal head 13 carrying a bolt or nut seat 14 defined by the spaced jaws 15, it being understood that the head is interchangeable with similar heads having seats 35 14 of different dimensions or having heads adapted to serve as pipe or rod-engaging means.

At its inner end the head is provided with a ratchet face 16 with which engages a pawl 40 17 pivoted as at 18 and housed in the bifurcated portion of the shank in position to terminally engage the teeth of the ratchet and thus hold the jaw in an adjusted position or permit it to feed in one direction as 45 the requirements of the operation of the tool may indicate. The pawl or dog is usually

held in operative position by a spring 19 secured to a pin 20 and having engagement with a bearing pin 21, while projecting from the rear or inner end of the pawl or dog is 50 an operating pin 22 which terminally projects beyond the contour of the edge of the shank in convenient position to be actuated to disengage the pawl or dog from the ratchet teeth. It will be noted that the pawl 55 or dog with its operating pin and actuating spring are located in the space between the side walls of the bifurcation in the shank so as to be completely housed and afford no interfering projections for contact with objects adjacent to the path of the tool in operation, so that the latter may be used in comparatively restricted or confined spaces without inconvenience.

What is claimed is:

A wrench having a bifurcated shank, a pivotal head mounted in the bifurcation of said shank and provided with a nut seat, the head at the inner end being of arcuate shape and provided with ratchet teeth concentrically disposed with reference to the pivot of the head, a pawl disposed in said bifurcation below the head, a pivot pin spanning the bifurcation and pivotally supporting the pawl, the said pivot being disposed to one 75 side of the axis of the shank, a leaf spring supported in the bifurcation and having a free end bearing against the pawl, the spring being supported on a pin spanning the bifurcation, a bearing pin disposed 80 against the spring to maintain the latter in contact with the pawl, and an operating pin connected with the pawl and disposed transversely with relation to the shank and having its free end exteriorly exposed for the 85 manual operation of the pawl in opposition to the pressure of the spring.

In testimony whereof they affix their signatures.

JAMES L. HICKEY.
JOHN KRACHT.
